(57) **CLAIM**

We claim the ornamental design for a utility vehicle body, as shown and described.

DESCRIPTION

FIG. 1 is a front perspective view of a utility vehicle body showing our new design;

FIG. 2 is a rear perspective view thereof;

FIG. 3 is a front elevational view thereof;

FIG. 4 is a rear elevational view thereof;

FIG. 5 is a left side elevational view thereof, which is a mirror image of the right side not shown; and,

FIG. 6 is a top plan view thereof.

The structural features depicted by means of broken lines in the drawing figures have been shown for the purpose of illustrating environmental structure only and form no part of the claimed design.
